UNITED STATES PATENT OFFICE

2,517,124

SNARE STRUCTURE FOR DRUMS

William F. Ludwig and Fred F. Kiemle,
Chicago, Ill.

Application December 15, 1945, Serial No. 635,265

1 Claim. (Cl. 84—415)

1

This invention relates to improvements in snare drums and in snare structures for drums and has for its object to provide a structure of this type which is very efficient, durable and of light weight and which can be produced in any desired width and number of snares.

A further object of the invention is to provide a helical wire snare structure wherein the outer end portions of the snares are prevented from cutting through the drum head skin.

Another object of the invention is to provide a drum structure and a helical wire snare structure therefor wherein cooperative means are provided for causing the snares to lie in contact throughout their entire lengths with a predetermined surface portion of the drum head when said snares are tensioned, with no portions of said snares bearing more firmly than other portions thereof upon the drum head.

A further object of the invention is to provide drum snares and plates to which the same are secured, wherein no part of either of said plates is brought into surface contact with the drum head when the said snares are tensioned, and wherein the total combined length of said snares and end plates is only such that the means connected with said end plates for tensioning said snares are caused to bear upon only the outermost marginal portion of the drum head.

A suitable embodiment of the invention is illustrated in the accompanying drawings wherein:

Fig. 1 is a fragmentary plan of a snare structure constructed in accordance with the invention.

Fig. 2 is a vertical transverse sectional view of the same taken on the line 2—2 of Fig. 1.

Fig. 3 is a fragmentary inverted perspective view, on a reduced scale, of a conventional type of snare drum equipped with a snare structure constructed in accordance with this invention.

Fig. 4 is a fragmentary enlarged detail sectional view taken on the line 4—4 of Fig. 3 on the scale of Figs. 1 and 5.

Fig. 5 is a detail fragmentary vertical sectional view showing an inner surface portion of the drum casing, taken on the line 5—5 of Fig. 4.

All figures of the drawing are in reverse or upside down.

The snare structure of the invention includes a pair of plates 1 and 2 composed of a suitable type of tough plastic material, such as certain types of Celluloid and others of the thermoplastic type.

The plates 1 and 2 may be made of any desired shape and thickness, but in the instance illus-

2

trated, they are substantially rectangular and present parallel opposed edges extending perpendicular to the axes of the snares 3.

In the instance illustrated, said snares 3 are of the helical wire type commonly used, but may be of any other suitable type.

The faces of the plates 1 and 2 are plane and smooth and preferably parallel with each other, the thickness of said plates being at least equal to the outer diameter of the snares or greater. They are shown as being of greater thickness than said snare diameter, in this instance, for the sole reason that the plastic material used must be of sufficient tensile strength to withstand the greatest tension to which the snares may be subjected in use.

The snares 3 are embedded into one face of each of the plates 1 and 2 along substantially equally long end portions to a substantially equal depth which is less than their diameter, as, for example, equal to eighty or ninety percent of the latter.

Each of the plates 1 and 2 is equipped with a pair of perforations 4 for purposes of attaching thereto the tensioning cords 5, shown in Figs. 1 and 4, which are attachable to whatever type of snare tensioning mechanism 6 that may be mounted upon the drum shell 7, said cords 5 being passed through openings 8 in the conventional drum head tensioning hoop 9, as shown in Fig. 4.

The snares 3 are equally spaced apart and parallel, and are perpendicular to the opposed parallel edges of plates 1 and 2 and the portions thereof projecting from the faces of said plates serve to maintain said plate faces spaced from the drum head, while the tension of said snares maintains said plates parallel with said head and thus also maintains the middle portions of the snares in contact with said head.

The cords 5 underlying the outer edge portions of the plates 1 and 2 serve as sufficient supports for said plate portions to prevent canting of the same when the snares 3 are tensioned by operation of the screw 13 or the lever 14, the latter or an equivalent thereof being common to many snare tensioning mechanisms.

Both ends of practically all sheet metal drum shells are equipped with terminal inwardly projecting arcuate annular flanges 12 over which the drum heads 10 are stretched, but in the instance illustrated, the lower edge of the shell 7 has its annular flange equipped with a pair of diametrically opposed depressions shown in Figs. 4 and 5 of arcuate length less than the width of

the plates 1 and 2, and into which portions of the drum head 10 are forced by the tensioning hoop 11.

These recesses formed by the flanges 12 are shallow and form shallow depressions in opposed marginal portions of the head 10, and are bridged by the plates 1 and 2.

The side edge portions of the latter are thus amply supported by the drum head 10 and thus maintained parallel with the latter against stress imposed upon the outer edge portions of said plates which might tend to cant them when the snares are tensioned. See Figs. 3, 4 and 5.

The cords 5 have their end portions extending downward through the openings 4 of the plates 1 and 2 and then outwardly underneath the same within the marginally recessed portions of the drum head, through these openings in and over the skirt portions of the hoop 9, and are then connected, respectively, with an anchoring device (not shown) and the snare tensioning mechanism 6 which includes an adjusting screw 13 and an operating lever 14. The skirt portion of the hoop 9 is arcuate in cross section, as shown in Fig. 4, and connected with conventional means (not shown) to draw them toward each other to tension the drum heads either in unison or independently of each other as is common practice in the art.

We claim as our invention:

A snare structure comprising a series of equally spaced apart parallel helical wire snares of equal diameter having their axes disposed in a plane parallel with the surface of the drum head upon which they bear when tensioned, a pair of sub-

stantially rectangular end plates of a thermoplastic material into which predetermined equal lengths of the end portions of said snares are embedded to equal depth with portions of said end portions of said snares projecting equally from one surface of each of said end plates, said surfaces of said plates being plane, the combined length of said plates and unembedded portions of said snares being less than equal to the outermost marginal edge of the drum head, said end plates being equipped with perforations to receive means for connecting the same with conventional snare tensioning mechanisms mounted upon the drum with said perforations positioned to cause portions of said connecting means to bear upon the said marginal portion of the drum head and thereby cooperating with said projecting end portions of the embedded parts of said snares to maintain said end plates spaced from the drum head when said snares are tensioned, the portions of said snares disposed between said end plates being of equal length.
